US00D950645S

(12) **United States Design Patent** (10) Patent No.: **US D950,645 S**
 Tollefsen et al. (45) Date of Patent: ** *May 3, 2022

(54) **DISPENSER**

(71) Applicant: **The Gorilla Glue Company LLC**, Cincinnati, OH (US)

(72) Inventors: **Trond Erik Tollefsen**, London (GB); **Ryan Joseph Boudreaux**, Yorktown Heights, NY (US); **Nicholas John Wagner**, Plano, IL (US); **Mitchell James Wagner**, Sugar Grove, IL (US); **Ryan David Mahoney**, Cincinnati, OH (US); **Kevin Jay Gampfer**, Milford, OH (US); **Jeremy Thomas Lacy**, Centerville, OH (US)

(73) Assignee: **The Gorilla Glue Company LLC**, Cincinnati, OH (US)

(*) Notice: This patent is subject to a terminal disclaimer.

(**) Term: **15 Years**

(21) Appl. No.: **29/715,109**

(22) Filed: **Nov. 27, 2019**

(51) LOC (13) Cl. **19-02**

(52) U.S. Cl.

USPC **D19/66; D19/934**

(57) **CLAIM**

The ornamental design for a dispenser, as shown and described.

DESCRIPTION

FIG. 1 is an isometric view of a dispenser showing our new design;

FIG. 2 is a rear view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

The broken lines in the drawings are included for the purpose of illustrating environmental structure and form no part of the claimed design.

1 Claim, 6 Drawing Sheets
